UNITED STATES PATENT OFFICE.

WILLIAM FAIRCHILD, OF ALBANY, NEW YORK, ASSIGNOR TO WILLIAM C. MARTINEAU
AND CLARENCE R. MARTINEAU, BOTH OF ALBANY, NEW YORK.

LOOSE-LEAF BINDER.

1,016,557.

Specification of Letters Patent. Patented Feb. 6, 1912.

Application filed February 24, 1911. Serial No. 610,588.

To all whom it may concern:

Be it known that I, WILLIAM FAIRCHILD, a citizen of the United States, residing at Albany, Albany county, New York, have 5 invented certain new and useful Improvements in Loose-Leaf Binders, of which the following is a specification.

My invention relates to loose-leaf binders or filing devices for holding a variable number 10 of sheets of paper or the like in superposition. Its object is to provide means for holding any desired number of such sheets closely together so that they may be readily referred to, written upon, detached, 15 replaced or added to, as desired, the device being simple, easily manipulated, efficient and durable.

Further objects and details of the invention will appear in this specification and be 20 pointed out in the claims.

In the drawings, Figure 1 is a perspective view of my device; Fig. 2 is a like view showing a number of sheets retained therein; Fig. 3 is a partial vertical section 25 through the plane 3—3, Fig. 2.

11 designates the lower cover of the binder, of which 12 is the back or clamp portion, 13, a hinge, and 14, a body.

15 is the upper cover, consisting as before 30 of a back or clamp portion 16, hinge 17 and body 18. Firmly secured to the back 12 of the lower cover 11, as by means of integral, transverse loops 19, are, in the present instance, two vertically disposed flexible stems 35 20, each of which consists of a close spirally wound wire body 21 and a solid pointed tip 22, the wire of which the body 21 is formed being preferably of spring temper. Secured to the upper face of the back 16 of the upper 40 cover 15 are two reinforcing blocks 23, which may be of wood, sheet metal or other suitable material. In each of these blocks is formed an aperture 24 registering with an aperture 25 in the back 16, these apertures being of a size to freely pass the stems 20 and so positioned that when the stems pass therethrough the covers 11 and 15 will be superposed. The apertures 24 in the blocks are preferably countersunk or tapered 45 50 to form a rounded shoulder, as shown in Fig. 3, the upper end of the aperture being at a distance below the top of the block substantially equal to the diameter of the stem 20. Secured to the upper face of each

of the blocks 23 is a metal plate 26, in which 55 is an aperture 27 registering with the apertures 24 and 25, and somewhat greater in diameter than the stem 20. Extending radially from the aperture 27 approximately to a front corner of the plate is a slot 28 60 slightly wider than the diameter of the stem 20. A corner 29 of the plate 26 adjacent the free end of the slot 28 is slightly bent down or depressed, for a purpose to be hereafter explained.

The operation of the device will be readily understood from an inspection of the drawings. It will be seen that when the flexible, resilient stems 20 stand in their vertical position, as in Fig. 1, the upper 70 cover 15 may be readily removed from the stems or replaced thereon. The upper cover being so removed, any desired number of sheets 30, of paper, cardboard, textile material or the like, previously perforated in the 75 usual manner, are slipped over the stems 20, the cover 15 replaced and pressed downward, and the stems 20 are bent down, first in a vertical plane through the slots 28, and then in a substantially horizontal plane under the corners 29 and beneath the free front portions of the plates 26. The depression of the corners 29 of the plates assists in preventing the accidental disengagement of the stems from their locked position. The manual bending down of the stems 20 acts to slightly stretch the lower or leaf-engaging portion of the stems below the bend, so that the resilient contraction of such lower portions serves to draw the backs or clamping 80 85 portions of the binder closely together, thereby holding the inclosed leaves under a constant, resilient pressure. This natural stretching movement of the stems may be voluntarily increased by the operator, if desired. The complete device, shown in Fig. 90 95 2, forms a book, which may be a loose-leaf ledger, book of samples, or the like. The book may be readily opened, by reason of the hinges 13 and 17 in the covers, the flexible stems 20 yielding freely to permit the swinging back of the upper cover 15. When sheets are to be removed or new ones added, the stems 20 are swung horizontally under the corners 29 and permitted to pass through 100 105 the slots 28 and to resume their vertical position, when the upper cover 15 may be removed.

It is obvious that many mechanical alterations may be made in my device without departing from my invention. Thus it is essential that the stems, which serve to connect the covers, shall be flexible and preferably resilient, and that a readily disengagable locking means shall be provided for holding the stems in their bent position with the sheets tightly clasped between the covers; but it is non-essential that the stems shall be formed of spirally coiled wire, or that the locking means shall be of the particular form described.

In Fig. 1 of the drawings, I have shown another feature of my invention. The back portions 12 and 16 of the respective covers 11 and 15, instead of being made of strips of binder's board covered with duck or other textile material as is customary, and as is shown in Fig. 2, are here made of sheet iron or other rigid metal strips 31 with their edges 32 turned up and preferably bent inward as shown. These strips are covered with sheets 33 of duck or like textile material, which extend to any desired distance both beneath and above the body portions 14 and 18 of the covers, and are glued together between the back and body portions to form the hinges 13 and 17. These metal backs are very rigid and durable and are especially adapted to my invention as already described, in that the space beneath the body of the strip in the back 12 receives the transverse loop 19 of the stem 20, which loop may be secured to the metal strip 31 by soldering or otherwise; and in that the edges 32 of the strip in the back 16 serve to engage the blocks 23, which are shouldered at their lower edges 23a for this purpose.

What I claim is:

1. A retaining device for a loose-leaf binder having upper and lower clamping portions, comprising a flexible stem secured to one of said clamping portions; and locking means rigidly secured to the other of said clamping portions with which said stem is adapted to be manually engaged for holding the latter in bent position with its free end substantially at a right angle with its leaf engaging portion.

2. A retaining device for a loose-leaf binder having upper and lower clamping portions, comprising a flexible, resilient stem secured to said lower clamping portion; and locking means rigidly secured to said upper clamping portion with which said stem is adapted to be manually engaged for holding the latter in bent position with its free end substantially at a right angle with its leaf engaging portion.

3. A retaining device for a loose-leaf binder comprising a flexible stem, and locking means for detachably holding said stem in bent position, said stem being engageable

with said locking means by being first bent in a vertical and afterward in a substantially horizontal plane.

4. A retaining device for a loose-leaf binder having upper and lower clamping portions, comprising a flexible, extensible stem consisting of a spirally coiled, resilient wire secured to said lower clamping portion; and locking means rigidly secured to said upper clamping portion with which said stem is adapted to be manually engaged for holding the latter in bent position with its lower leaf-engaging portion slightly extended.

5. A retaining device for a loose-leaf binder having upper and lower clamping portions, comprising a flexible stem consisting of a spirally coiled, resilient wire secured to said lower clamping portion; and locking means rigidly secured to and above said upper clamping portion with which said stem is adapted to be manually engaged for holding the latter in bent position with its free end above and substantially parallel with said upper clamping portion.

6. A retaining device for a loose-leaf binder having upper and lower clamping portions, comprising a flexible stem secured to said lower clamping portion, and manually engageable locking means, including a metal plate rigidly secured above said upper clamping portion and having an aperture adapted to pass said stem and a slot extending from said aperture to the periphery of said plate, for detachably holding said stem in bent position.

7. A retaining device for a loose-leaf binder comprising a flexible stem, and locking means, including a slotted metal plate having a depressed corner under which said stem passes, for detachably holding said stem in bent position.

8. A loose-leaf binder comprising a lower cover; an apertured upper cover; a flexible, resilient stem secured to said lower cover and passing through the aperture in said upper cover; and locking means rigidly secured above said upper cover with which said stem is adapted to be manually engaged for holding the latter in bent position.

9. A loose-leaf binder comprising upper and lower covers; a reinforcing block on said upper cover; said upper cover and said block having registering apertures, the aperture in said block having a tapered enlargement; a flexible stem secured to said lower cover and passing through the apertures in said upper cover and said block; and locking means on said upper cover for detachably holding said stem in bent position.

10. A loose-leaf binder comprising upper and lower covers; a reinforcing block on said upper cover; a locking plate on said block, said upper cover, said block and said plate having registering apertures, said

plate also having a slot extending from the aperture therein to its periphery; a flexible stem secured to said lower cover and passing through all said apertures and adapted to be bent downward so as to pass through said slot and to be engaged beneath said plate.

11. In a loose-leaf binder, an upper cover including a back, a hinge and a body; said back including a trough-shaped, metal strip having longitudinal, upturned edges; a sheet of flexible material embracing said metal strip, extending over and secured to said body, and forming said hinge; and a reinforcing block rigidly secured to said metal strip and extending above said strip and said flexible sheet, and having a shouldered portion engaged between the edges of said strip.

12. A loose-leaf binder comprising upper and lower covers, said covers each including a back portion consisting of a metal strip

having longitudinal bent edges and a sheet of textile material surrounding said strip; a flexible stem secured to the metal strip in said lower cover; a reinforcing block secured to the metal strip in said upper cover, said block having a shouldered portion engaged between the edges of said strip; a locking plate on said block, said upper cover, said block and said plate being provided with registering apertures, said plate being also provided with a slot extending from the aperture therein to its periphery; said stem being adapted to pass through all said apertures and to be bent downward so as to pass through said slot and to be engaged beneath said plate.

WILLIAM FAIRCHILD.
